CLAIM

The ornamental design for aerosol-generating capsule as
shown and described.

DESCRIPTION

FIG. 1 is a top right, front perspective view of an aerosol-generating capsule according to a new design.

FIG. 2 is a top left, front perspective view of the aerosol-generating capsule of FIG. 1.

FIG. 3 is a top right, rear perspective view of the aerosol-generating capsule of FIG. 1.

FIG. 4 is a top left, rear perspective view of the aerosol-generating capsule of FIG. 1.

FIG. 5 is a bottom right, front perspective view of the aerosol-generating capsule of FIG. 1.

FIG. 6 is a bottom left, front perspective view of the aerosol-generating capsule of FIG. 1.

FIG. 7 is a bottom right, rear perspective view of the aerosol-generating capsule of FIG. 1.

FIG. 8 is a bottom left, rear perspective view of the aerosol-generating capsule of FIG. 1.

FIG. 9 is a front view of the aerosol-generating capsule of FIG. 1.

FIG. 10 is a rear view of the aerosol-generating capsule of FIG. 1.

FIG. 11 is a first side view of the aerosol-generating capsule of FIG. 1.

FIG. 12 is a second side view of the aerosol-generating capsule of FIG. 1.

FIG. 13 is a top view of the aerosol-generating capsule of FIG. 1; and,

FIG. 14 is a bottom view of the aerosol-generating capsule of FIG. 1.

The broken lines in the drawings depict portions of the
aerosol-generating capsule that form no part of the claimed
design.

1 Claim, 14 Drawing Sheets
